UNITED STATES PATENT OFFICE.

GEORGE M. BELLASIS, OF LAKEFIELD, CANADA.

LIQUID-MEASURING DEVICE.

SPECIFICATION forming part of Letters Patent No. 460,423, dated September 29, 1891.

Application filed April 2, 1891. Serial No. 387,348. (No model.)

To all whom it may concern:

Be it known that I, GEORGE M. BELLASIS, of Lakefield, in the Province of Ontario, Dominion of Canada, have invented a new and 5 useful Improvement in Liquid-Measuring Devices, of which the following is a full, clear, and exact description.

The object of the invention is to provide a new and improved liquid-measuring device, 10 which is simple and durable in construction, and serves to automatically close the faucet when the proper quantity of the liquid has passed through the said faucet and into the vessel, so as to prevent overflow and loss of 15 the liquid, at the same time measuring the desired amount of the liquid passed into the vessel.

The invention consists of certain parts and details and combinations of the same, as will 20 be fully described hereinafter, and then pointed out in the claims.

Reference is to be had to the accompanying drawings, forming a part of this specification, in which similar letters of reference indicate 25 corresponding parts in both the figures.

Figure 1 is a side elevation of the improvement with parts in section, and Fig. 2 is a plan view of the same.

The improved liquid-measuring device is 30 provided with a suitably-constructed base A, on which is erected a post B, carrying a pivot C, on which is hung the scale-beam D, provided near one end with a suitable graduation, and on which is hung a poise E. The 35 other end of the scale-beam D is pivotally connected with a rod F, projecting from the under side of a pan G, adapted to support the vessel H, into which the liquid is to be measured.

For conveniently filling the vessel H with the liquid a funnel I is held in the neck of the vessel, the said funnel being preferably provided with a float I' for closing the lower end of the funnel when the liquid rises to the 45 desired height in the vessel H. Into the funnel I is adapted to discharge the faucet J, held in the tank, barrel, or other receptacle K, containing the liquid to be filled into the vessel H. The valve J' of the faucet J is connected with an arm L, pivotally connected at 50 its ends with parallel links N and N', pivoted to a lever O, fulcrumed on a bracket B', pro-

jecting from the upper end of the post B. The pivot of the lever O, connecting the latter with the link N, is connected with one end of 55 a rope or cord P, passing over a pulley Q, journaled in the upper end of the post B.

The downwardly-extending end of the rope or cord P is connected with a weight R, fitted to slide loosely on the post B, and is adapted 60 to be supported by the upper end of an arm D', projecting upward at a right angle from the scale-beam D and adapted to slide into a recess or slot in the post B, so as to permit the weight R to slide down on the post B, as 65 hereinafter more fully described.

The rod F, near its lower end, is pivotally connected with one end of a lever S, pivoted centrally at S' on the post B below the pivot C. The other end of the lever S is pivotally 70 connected with a link T, pivoted to the beam D at a point equidistant to that part of the lever S extending from its pivot S' to its pivotal connection with the rod F.

On the lever S is formed a scale, and on this 75 part of the lever is hung a poise U, serving to counterbalance the weight of the empty vessel H.

The device is used as follows: The vessel H, into which the liquid is to be measured, is 80 placed on the pan G, and then the poise U is adjusted on the lever S, so that the scale-beam D stands horizontally. The poise E is then hung on the beam D at a point indicated on the graduation of the beam and representing the amount of liquid to be measured into the vessel H. The weight of the poise E causes the outer end of the beam D to swing downward so that the vessel H rises, the downward movement of the beam being 85 limited by the lower end of the link T, resting on top of the base A. (See Fig. 1.) When the beam D is in this position, the arm or tongue D' extends with its upper end out of the slot or recess of the post B, so as to support the weight R. The operator now opens the valve J' of the faucet J, so that the liquid from the barrel, tank, or other receptacle K flows through the said faucet into the funnel I and from the latter into the vessel H. When 90 the desired quantity of liquid has passed into the vessel H, then the scale-beam D is counterbalanced and moves into a horizontal position. By this movement the arm or tongue 95

D' moves into the slot or recess in the post B, thus permitting the weight R to slide downward on the post B. The downward movement of the weight R exerts a pull on the rope or cord T, so that the lever O is caused to swing and by the links N N' and the arm L turns the valve J' of the faucet J, so as to close the latter. Thus the vessel H contains an amount of liquid to which the 10 poise E has been set on the beam D. Thus it will be seen that no attention whatever is required from the operator to turn off the faucet J after the desired amount of liquid has been measured into the vessel H, as the 15 movement of the scale-beam D causes an automatic closing of the valve of the faucet J. Overflow and waste of the liquid are thus prevented.

Having thus described my invention, I 20 claim as new and desire to secure by Letters Patent—

1. In a liquid-measuring device, the combination, with a post, of a scale-beam pivoted on the said post and provided with an upwardly-extending arm or tongue, the said scale-beam being adapted to support a vessel, a weight fitted to slide on the said post and adapted to be supported on the arm or tongue of the scale-beam, and a device, substantially as described, connected with the said weight and with the faucet discharging into the said vessel, so that when the latter is filled with the proper amount of liquid the scale-beam is actuated and its arm or tongue 25 is disconnected from the said weight, so that the latter actuates the said device to turn off the faucet, as set forth.

2. In a liquid-measuring device, the combination, with a post, of a scale-beam pivoted on the said post and provided with a tongue or arm, a pan held on the said scale-beam and adapted to support a vessel, a weight fitted to slide on the said post and adapted to be supported on the said tongue or arm of the said scale-beam, a cord or rope connected with the said weight, a lever connected with the said rope or cord, parallel links connected with the said lever, and an arm connected with the said links and with the valve of the faucet discharging into the said vessel, substantially as shown and described.

3. In a liquid-measuring device, the combination, with a post, of a scale-beam pivoted on the said post and provided with a tongue or arm, a pan held on the said scale-beam and adapted to support a vessel, a weight fitted to slide on the said post and adapted to be supported on the said tongue or arm of the said scale-beam, a cord or rope connected with the said weight, a lever connected with the said rope or cord, parallel links connected with the said lever, an arm connected with the said links and with the valve of the faucet discharging into the said vessel, and a graduated lever and a poise hung thereon 60 and connected with the said scale-beam, substantially as shown and described.

GEORGE M. BELLASIS.
